(57) **CLAIM**

The ornamental design for an electronic cigarette, as shown and described.

DESCRIPTION

The patent or application file contains at least one drawing executed in color. Copies of this patent or patent application publication with color drawing(s) will be provided by the Office upon request and payment of the necessary fee.

1. Electronic cigarette

1.1 : Perspective

1.2 : Perspective

1.3 : Front

1.4 : Back

1.5 : Left

1.6 : Right

1.7 : Top

1.8 : Bottom

The present design relates to an electronic cigarette; As can be seen from the drawings, the main body is of a cube-like structure, an upper portion of the main body protrudes to the side, which increases the peripheral perimeter; the peripheral perimeter of the upper end of the main body gradually reduces to form a nozzle; four edges of the side surfaces of the main body are provided with a chamfered rounded structure; and a lower end of the main body is of a domed structure.
